Patented Nov. 22, 1921.

Frederick Roettges,

Inventor

By his Attorneys, Dodson & Loc.

UNITED STATES PATENT OFFICE.

FREDERICK ROETTGES, OF STAMFORD, CONNECTICUT, ASSIGNOR TO WILLIAM R. NOE & SONS, OF NEW YORK, N. Y., A COPARTNERSHIP.

DESIGN FOR A LAMP OR OTHER PEDESTAL.

59,777.

Specification for Design.

Patented Nov. 22, 1921.

Application filed October 21, 1921. Serial No. 509,423. Term of patent 8½ years.

To all whom it may concern:

Be it known that I, FREDERICK ROETTGES, a citizen of the German Republic, residing at Stamford, in the county of Fairfield and State of Connecticut, have invented a new, original, and ornamental Design for a Lamp or other Pedestal, of which the following is a specification, reference being had to the accompanying drawing, forming part thereof.

The figure is a perspective view of a pedestal, showing my new design.

I claim—

The ornamental design for a lamp or other pedestal, as shown.
